(57) **CLAIM**

The ornamental design for a display screen with animated graphical user interface, as shown and described.

DESCRIPTION

FIG. 1 illustrates a first view in a sequence of a display screen with animated graphical user interface.

FIG. 2 illustrates a second view in the sequence of the display screen with animated graphical user interface.

FIG. 3 illustrates a third view in the sequence of the display screen with animated graphical user interface.

FIG. 4 illustrates a fourth view in the sequence of the display screen with animated graphical user interface.

FIG. 5 illustrates a fifth view in the sequence of the display screen with animated graphical user interface; and,

FIG. 6 illustrates a sixth view in the sequence of the display screen with animated graphical user interface.

The appearance of the transitional image sequentially transitions between the images shown in FIGS. 1-6. This process or period forms no part of the claimed design. The broken lines, which depict a display screen and the remainder of the graphical user interface, are provided for the purpose of illustrating environment and context, and form no part of the claimed design.
